DESIGN FOR A HEATER

Earl C. Booth, Columbus, Ind., assignor to Nob-
litt-Sparks Industries, Inc., Columbus, Ind., a
corporation of Indiana

Application September 8, 1938, Serial No. 79,772

Term of patent 7 years

To all whom it may concern:

Be it known that I, Earl C. Booth, a citizen
of the United States, residing at Columbus, Bar-
tholomew County, Indiana, have invented a new,
original, and ornamental Design for a Heater,
of which the following is a specification, refer-
ence being had to the accompanying drawing,
forming part thereof.

Fig. 1 is a top plan view, Fig. 2 is a side eleva-
tion, and Fig. 3 is a front elevation of a heater
showing my new design.

I claim:

The ornamental design for a heater, as shown.

EARL C. BOOTH.
